UNITED STATES PATENT OFFICE.

ALBIN ABRAHAMS, OF SPOKANE, WASHINGTON.

DESIGN FOR A FRUIT AND NUT DISH.

Application filed September 7, 1927. Serial No. 23,322. Term of patent 7 years.

Whom it may concern:
known that I, ALBIN ABRAHAMS, a
of the United States, residing at
, in Spokane County, and State of
ton, have invented a new, original,
amental Design for Fruit and Nut
of which the following is a specifica-
erence being had to the accompany-
ring, forming a part thereof.

Figure 1 is a plan view showing my new
design of a fruit and nut dish.

Figure 2 is an elevation of the same.

I claim:

The ornamental design for a fruit and
nut dish, as shown.

ALBIN ABRAHAMS.
